UNITED STATES PATENT OFFICE.

SAMUEL A. NEIDICH, OF EDGEWATER PARK, NEW JERSEY.

BRAID HANK-WINDING MECHANISM.

Application filed March 25, 1926. Serial No. 97,224.

This invention was designed for making commercial packages of braids of artificial horsehair, rayon, and other materials, especially intended for the millinery trade. 5 That trade demands braid in packages of uniform length, for instance one hundred forty four yards, preferably made up in a plurality of long parallel coils, in which the braid is continuous from coil to coil. The 10 purpose and effect of this invention is to provide a mechanism for winding and measuring such packages with a minimum amount of attention on the part of the operator and to present each completely wound 15 hank with its coils in such relation that they may be bound together by manually applied bands of string before removal of the hank from the winding mechanism.

However, it is to be understood that my 20 invention may be utilized in winding tapes, ribbons, or any narrow webbing or cord, in such associated coils.

My invention includes the various novel 25 features of construction and arrangement hereinafter more definitely specified.

In said drawings; Fig. I is a plan view 30 of a mechanism conveniently embodying my invention.

Fig. II is an elevation of the left hand 35 side of the mechanism as shown in Fig. I.

Fig. III is an elevation of the right hand 40 end of said mechanism as shown in Fig. II; being the lower end thereof as shown in Fig. I.

Fig. IV is a plan view of the completed 45 hank indicated in dotted lines in Fig. I.

Fig. V is an elevation of the right hand 50 side of said hank as indicated in Fig. IV.

Fig. VI is an inverted plan view of said 55 hank as shown in Fig. IV.

Fig. VII is a fragmentary plan view of 60 the winding head shown in Fig. I, but with the movable blade retracted to position to release the hank from said head.

In said figures; the frame 1 is provided 65 with bearings 2 and 3 for the winding shaft 4, which is provided with means, for instance, the belt wheel 5 and, or, the crank handle 6, whereby it may be rotated. As indicated by the dotted lines in Fig. I, the braid 7 is wound in a hank 8 on the winding head 9 which is detachably secured on said shaft 4, at one end thereof, conveniently by the set screw 10. Said head includes a bar 70 extending in diametrical relation with said shaft 4 and having slots 11 and 12 extending

in its ends in planes parallel with the axis of said shaft 4. The blades 13 and 14, which extend in the respectively opposite end bights of said hank 8 of braid and are 75 respectively carried in said slots 11 and 12, each include a tubular screw threaded shank 15 fitted to extend through one of said slots and provided with a nut 16; whereby, the center to center distance between said blades 80 may be adjustably varied, to precisely pre-determine the length of braid to be wound in said hank 8; say 144 yards.

Each of said blades has an axial duct 17 leading to a groove 18 in its radially outer 85 edge, parallel with the axis of said shaft 4, and in line with a radial slot 19 in a circular, braid abutment, flange 20. Each blade also has a spring clip 21 at the outer end thereof which may be used to secure 90 the end of a string extending through said duct and groove, to be used to bind the hank 8, as hereinafter described.

Said blade 13 has the pin 22 so spaced in 95 parallel relation therewith, adjoining the abutment flange 20, that the initial end of the braid 7 may be wedged between said pin and blade to secure it at the beginning of each winding operation. Said blade 13 may be rigidly secured in adjusted radial position in said head 9, by its nut 16. However,

the other blade 14 has its screw threaded shank 15 extending through the slot 23 in the carriage 24, in which it is secured by its nut 16; so as to be movable toward said 100 shaft 4 to release the hank 8. Said carriage is fitted to reciprocate in the slot 12 in said bar 9 and I provide means arranged to shift said carriage 24 and its blade 14 in said bar, including the crank 25 carried by 105

the shaft 26 which extends transversely in said bar and is pivotally connected to one end of the link 27 which has its other end connected to said carriage 24. Said crank 25 may be rocked by the operating handle 110 28 on said crank shaft 26; and the stop pin 30 on said bar limits the movement of said handle; so that said crank 25 and link 27 are operable as a toggle connection between said carriage and bar, and said carriage is

normally maintained at the outer limit of its movement with said operating handle 28 against said stop pin, and said link 27 past the dead center; so that said blade 14 is not accidentally displaced by the strain of wrapping the hank of braid 8 around said blades. 115 The abutment plate 31 is carried by said

bar 9 to which it is rigidly attached by the studs 33, and extends between said blades 13 and 14 in alinement with the braid abutment flanges 20 on said blades; so that said braid hank 8 may be pressed against said abutments to straighten and tie it, as herein-after described.

I provide means arranged to direct said braid 7 in successive positions for winding a plurality of coils thereof upon said blades, and to automatically shift to the successive positions of the respective coils, including the slide bar 35, which is mounted to slide in the bearings 36 and 37 on said frame 1, parallel with said shaft 4. The pair of guide roller shafts 38 are fixed in parallel spaced relation on the plate 29 which extends transversely in rigid connection with one end of said slide bar 35. The pair of braid guide rollers 41 have flanges 42 to receive the braid 7 between them and are mounted to turn idly on the respective roller shafts 38 in positions determined by the axially adjustable collars 43, which are rigidly connected with said shafts upon axially opposite sides of said braid guide rollers 41. The friction disks 45, conveniently formed of vulcanized fiber, are interposed between said guide rollers 41 and said collars 43; so that movement of said braid 7 toward said winding head is retarded by the resistance of said rollers 41 to turning movement. Moreover, I provide the braid tension device, including the stationary guide plate 47 which is rigidly mounted upon the bracket 48 which is detachably rigidly connected with said slide bar 35, by the set screw 49. Said plate 47 has two pairs of studs 51 fixed therein, forming a path between them for the braid 7 which is frictionally engaged by the pressure plate 53 which is pressed toward said plate 47 by the spring 54. Said bracket 48 is so set on said bar 35 that the passageway between said tension plates 47 and 53 is in alinement with the passageway between the guide flanges 42 on said guide rollers 41.

I provide means arranged to shift said slide bar 35, step by step, axially, with respect to said winding head 9, including a series of ratchet teeth 55, on the under side of said bar 35, and the pawl 56 which is conveniently formed of spring sheet metal and arranged to selectively engage said teeth 55. Said pawl 56 is rigidly connected at one end, by the screws 57, with the pawl plunger 58 which is mounted to reciprocate in said bearings 36 and 37, parallel with said slide bar 35. The spring 60 encircling said plunger 58 normally tends to thrust it to the outer extreme of its range of movement, and the effective pressure of said spring may be adjustably varied by shifting the pair of jam nuts 61 on said plunger in engagement with the screw thread 62 on the latter. The

stop pin 63 on said plunger is arranged to limit the outward movement of said plunger effected by said spring 60. In order to prevent accidental displacement of said plunger 58, I provide said slide bar 35 with a series of detent rack notches 65 adapted to be successively engaged by the detent plunger 66 which is mounted to reciprocate in the tubular bearing 68 which is rigidly connected with said bearings 36 and 37 and incloses the spring 70 which tends to thrust said plunger into engagement with the detent notches in said bar 35. Said detent 66 is provided with the cross pin 71 which normally extends in the diametrically opposite slots 72 in said tubular bearing 68 and presents said detent in position to engage said notches. I provide said detent with the knob 73 by which it may be retracted and rotated to turn said pin 71 aside from said notches 72, to hold said detent in idle position, whenever it is desired to freely slide said bar 35.

However, the function of said detent 66 is to normally prevent accidental displacement of said slide bar 35 carrying said braid guide rollers 41, but to yield and permit said bar to be shifted to the successive axial positions corresponding with the successive coils of the braid 7 in the hank 8, as indicated in dotted lines in Fig. I, when said bar 35 is thrust outwardly by said pawl 56. In order to effect the proper movement of said pawl plunger 58, in proper time with the winding operation of said shaft 4; I provide the latter with the worm 75 between said bearings 2 and 3 on the frame 1, in engagement with the worm gear 76 which is rigidly connected with the end of the cam shaft 77 which is journaled in the bearings 78 and 79 on said frame 1, and provide the opposite end of said cam shaft with the pawl cam 81 arranged to engage the cam plate 82 projecting from said pawl plunger 58 so as to retract said plunger, against the stress of its spring 60, and release said plunger to be operated by said spring, once each revolution of said cam shaft 77. Only the hub of said worm gear 76 appears in Fig. I, but it is indicated in connection with the worm gear 75 in Fig. III. When thus retracted and released, said plunger 58 is moved outwardly by its spring 60, with said pawl 56 engaging a ratchet tooth 55 on the under side of said slide bar 35; so that said slide bar is shifted outwardly against the pressure of said detent 66, forcing the latter out of the notch 65 in said slide bar with which it is engaged, and permitting it to return into the next succeeding notch. Such movement shifts the guide rollers 41 outwardly to the extent of the width of the braid 7, so as to direct the latter to form the next succeeding coil in the hank 8.

The tension upon said braid 7 induced by

the friction disks 45 upon said guide rollers 41, and by the passage of the braid between said tension plates 47 and 53, is constant, although subject to adjustment as above described. However, as each coil of braid is wound over said blades 13 and 14, an increasing extent of braid is required for each convolution. In other words; with the winding shaft 4 turning at a constant speed, the braid 7 must be wound in the coils at a speed which increases from the first to the last convolution in each coil. Therefore, I prefer to also provide said mechanism with means whereby the tension upon the braid may be automatically varied, in correspondence with the speed at which the braid is taken up in the winding operation; so that the tension upon the braid is decreased as its speed of travel is increased in the winding of each coil. In the form shown; such means includes the fork 84 having the pair of cylindrical tines 85, in spaced relation, and engaged with the braid 7 between said tension plate 53 and said guide rollers 41. Said fork is carried by the rock shaft 86 which is journaled in the brackets 87 on said frame 1, parallel with said winding shaft 4. Said fork shaft 86 has the crank 88 connected by the link 89 and pivotal coupling 90 with the fork actuating lever 91 which has the fulcrum 92 on said frame 1 and is provided with the spring 93 connecting said fork lever with said frame and tending to shift said lever and fork to one extreme of their range of movement. Said fork actuating lever 91 has the cam stud 95 arranged to cooperate with the crown cam 96 on said cam shaft 77, to gradually shift said fork lever 91 and turn said fork from one extreme to the other during each revolution of said cam shaft 77; one such revolution being effected during the winding of each of said coils of the braid 7 in the hank 8, and with the effect of varying the tension upon the braid as above contemplated.

When the hank 8 is completely wound, the machine is stopped and the binder tie 97, conveniently consisting of a band of string, is tightly wrapped around the hank 8 and knotted at 98 as shown in Fig. IV; the braid 7 is then cut with the last end thereof projecting beyond said tie, toward the upper portion of Fig. IV, and the cut end of the braid 7 then tucked under said tie 97 to secure it, as shown in said figure. I find it convenient to provide each hank with at least two other binder ties 99 which are tightly wrapped around it and knotted at 100. I also find it convenient to provide each hank with a hanger tie 101 formed of a loose bight of string, knotted at 103.

The string 105 for said binder ties 97 and 99 and hanger 101 is conveniently carried upon the two spools 106 which are journaled on the spindles 107 rigidly projecting from

said winding head 9, respectively adjacent to said blades 13 and 14, and provided with pins 109 and washers 110 to prevent their accidental displacement. Said string is directed from the respective spools through the adjacent ducts 17 and grooves 18 of the respective blades 13 and 14 and the free ends of the strings are temporarily fastened under the spring clips 21 on the respective blades.

Said mechanism is operated as follows: The mechanism being in the position shown in Figs. I and II; the braid 7 is drawn from a supply roll or reel and threaded between the tension plates 47 and 53 and around the fork tines 85 and over and under the respective guide rollers 41, as shown in Fig. II, and the forward end of the braid caught between said pin 22 and the adjacent face of the blade 13. Thereupon, said shaft 4 is turned in the direction of the arrow shown in Fig. II and said braid wound in a coil adjacent to the flanges 20 and plate 31 until thirty convolutions have been wound in that initial coil of the hank 8. During such winding, the crown cam 96 gradually shifts said fork lever 91 and turns said fork 84 to vary the tension on said braid in compensation for the increased speed of traverse of the braid incident to the increased extent of the convolutions in said coil. As the winding of said coil is completed, the crest of said crown cam 96 is carried past said stud 95, thus releasing said lever 91 from the extreme position to which it has been thrust, and permitting its spring 93 to return it to the initial position shown in Fig. I. Contemporaneously, said pawl plunger 58 having been retracted by the pawl cam 81 and released, is thrust by its spring 60 so as to engage said slide bar 35 by the pawl 56 and shift said bar 35 outwardly to the extent of one of its ratchet teeth 55, against the frictional engagement of said detent 66 which falls into the next succeeding notch 65 to the right in Fig. I. Continued rotation of said winding shaft 4 and head 9 winds the braid in a second coil on said head 9, adjacent to said first coil; the braid 7 crossing from one coil to another, as indicated by the diagonal lines 112 in Fig. VI. The operation is continued until seven coils are wound to form the hank 8 and, thereupon, the winding operation is suspended while the hank is bound with the string ties, as above described. Thereupon, the operation above described is repeated to form another hank 8.

Although I have found it convenient to form hanks 8 of seven coils, each containing thirty convolutions; it is obvious that such specific numbers of coils and convolutions are not of the essence of my invention; the apparatus above described being adjustable to vary the same.

Therefore, I do not desire to limit myself

to the precise details of construction and arrangement herein set forth, as it is obvious that various modifications may be made therein without departing from the essential features of my invention, as defined in the appended claims.

I claim:

1. In a braid hank winding mechanism, the combination with a frame; of a winding shaft mounted to rotate in said frame; means on said shaft, including a belt wheel, whereby it may be rotated; a winding head detachably secured on said shaft, at one end thereof, including a bar extending in diametrical relation with said shaft and having slots extending in its ends in planes parallel with the axis of said shaft; blades respectively carried in said slots, each including a screw threaded shank fitted to extend through one of said slots and provided with a nut; each of said blades having a circular braid abutment flange fixed thereon adjacent to its screw threaded end and having a tie groove in its radially outer edge, parallel with the axis of said shaft and extending through the blade flange; a carriage for one of said blades, fitted to reciprocate in said bar, local to one of the slots in the latter; means arranged to vary the radial position of said carriage and its blade in said bar, including a crank carried by a shaft extending transversely in said bar, and a link pivotally connected at one end to said carriage and at the other end to said crank, an operating handle on said crank shaft, and a stop pin on said bar; whereby said crank and link are operable as a toggle connection between said carriage and bar.

2. In a braid hank winding mechanism, the combination with a frame; of a winding shaft mounted to rotate in said frame; means on said shaft whereby it may be rotated; a winding head secured on said shaft, at one end thereof, including a bar extending in diametrical relation with said shaft and having slots extending in its ends in planes parallel with the axis of said shaft; blades respectively carried in said slots; each of said blades having a braid abutment flange thereon adjacent to its screw threaded end and having a tie groove in its radially outer edge, a carriage for one of said blades, fitted to reciprocate in said bar, local to one of the slots in the latter; means arranged to vary the radial position of said carriage and its blade in said bar, including a crank carried by a shaft extending transversely in said bar, and a link pivotally connected at one end to said carriage and at the other end to said crank; whereby said crank and link are operable as a toggle connection between said carriage and bar.

3. In a braid hank winding mechanism, the combination with a frame; of a winding shaft mounted to rotate in said frame;

means on said shaft whereby it may be rotated; a winding head secured on said shaft, at one end thereof, including a bar extending in diametrical relation with said shaft and having slots extending in its ends in planes parallel with the axis of said shaft; blades respectively carried in said slots; each of said blades having a braid abutment flange thereon; a carriage for one of said blades, fitted to reciprocate in said bar, local to one of the slots in the latter; and means arranged to vary the radial position of said carriage and its blade in said bar.

4. In a braid hank winding mechanism, the combination with a frame; of a winding shaft mounted to rotate in said frame; means on said shaft whereby it may be rotated; a winding head on said shaft, including two blades respectively carried on opposite sides of said shaft; each of said blades having a braid abutment flange thereon; means arranged to direct braid to said blades, in successive positions for winding a plurality of coils thereon, and to intermittently shift to the successive positions for the respective coils, including a slide bar mounted to slide in bearings on said frame parallel with said shaft; a pair of guide roller shafts fixed on said slide bar, in spaced parallel relation therewith; a pair of guide rollers mounted to turn idly on said roller shafts; a tension device including a stationary guide plate carried by said slide bar, and a spring pressed plate opposed to said stationary plate, arranged to press a braid between them; the passageway between said plates being in alignment with said guide rollers; means arranged to shift said slide bar, step by step, axially with respect to said winding head, including a series of ratchet teeth on said bar, a pawl arranged to selectively engage said teeth, a pawl plunger, carrying said pawl, and mounted to reciprocate in bearings in said frame parallel with said slide bar, and a spring encircling said plunger, normally tending to thrust it to one extreme of its range of movement; a series of detent rack notches in said slide bar, and a spring pressed detent plunger arranged to successively engage said detent notches; and means arranged to actuate said pawl, at the completion of each coil; whereby said slide bar carrying said guide rollers and tension device is normally detained in stationary position by said detent, but is intermittently shifted to the extent of one of said ratchet teeth, at the completion of winding a single coil in said hank.

5. In a braid hank winding mechanism, the combination with a frame; of a winding shaft mounted to rotate in said frame; means on said shaft whereby it may be rotated; a winding head on said shaft, including two blades respectively carried on opposite sides of said shaft; each of said blades having a

braid abutment flange thereon; means arranged to direct braid to said blades, in successive positions for winding a plurality of coils thereon, and to intermittently shift to the successive positions for the respective coils, including a slide bar mounted to slide in bearings on said frame parallel with said shaft; a pair of guide roller shafts fixed on said slide bar, in spaced parallel relation therewith; a pair of guide rollers mounted to turn idly on said roller shafts; a tension device including a stationary guide plate carried by said slide bar, and a spring pressed plate opposed to said stationary plate, arranged to press a braid between them; the passageway between said plates being in alinement with said guide rollers; means arranged to shift said slide bar, step by step, axially with respect to said winding head, including a series of ratchet teeth on said bar, a pawl arranged to selectively engage said teeth, a pawl plunger, carrying said pawl, and mounted to reciprocate in bearings in said frame parallel with said slide bar, a spring normally tending to thrust said plunger to one extreme of its range of movement; means arranged to adjustably vary the pressure of said spring; means on said plunger arranged to limit the range of its movement by said spring; a series of detent notches in said slide bar, and a detent arranged to successively engage said detent notches; means arranged to actuate said pawl, at the completion of each coil, including a worm on said winding shaft; a worm gear engaging said worm; a cam shaft carrying said worm gear, journaled in bearings on said frame; and a pawl cam on said cam shaft, arranged to engage said pawl plunger, retract said plunger against the stress of said spring, and release said plunger to be operated by said spring, once each revolution of said cam shaft; whereby said slide bar carrying said guide rollers and tension device is normally detained in stationary position by said detent, but is intermittently shifted to the extent of one of said ratchet teeth, at each revolution of said cam shaft, which corresponds with the completion of winding a single coil in said hank.

30 successively engage said detent notches; means arranged to actuate said pawl, at the completion of each coil; whereby said slide bar carrying said guide rollers and tension device is normally detained in stationary position by said detent, but is intermittently shifted to the extent of one of said ratchet teeth, at each revolution of said cam shaft, which corresponds with the completion of winding a single coil in said hank.

40 35 40 45 50 55 60 65 70 75 80 85 90 95 100 105 110 115 120 125 130

cluding a stationary guide plate carried by said slide bar and a spring pressed plate opposed to said stationary plate, arranged to press a braid between them; the passageway between said plates being in alinement with said guide rollers; means arranged to shift said slide bar, step by step, axially with respect to said winding head, including a series of ratchet teeth on said bar, a pawl arranged to selectively engage said teeth, a pawl plunger, carrying said pawl, and mounted to reciprocate in bearings in said frame parallel with said slide bar, a spring normally tending to thrust said plunger to one extreme of its range of movement; means arranged to adjustably vary the pressure of said spring; means on said plunger arranged to limit the range of its movement by said spring; a series of detent notches in said slide bar, and a detent arranged to successively engage said detent notches; means arranged to actuate said pawl, at the completion of each coil, including a worm on said winding shaft; a worm gear engaging said worm; a cam shaft carrying said worm gear, journaled in bearings on said frame; and a pawl cam on said cam shaft, arranged to engage said pawl plunger, retract said plunger against the stress of said spring, and release said plunger to be operated by said spring, once each revolution of said cam shaft; whereby said slide bar carrying said guide rollers and tension device is normally detained in stationary position by said detent, but is intermittently shifted to the extent of one of said ratchet teeth, at each revolution of said cam shaft, which corresponds with the completion of winding a single coil in said hank.

7. In a braid hank winding mechanism, the combination with a frame; of a winding shaft mounted to rotate in said frame; means on said shaft whereby it may be rotated; a winding head detachably secured on said shaft, having slots extending in its ends; blades respectively carried in said slots; means for adjustably securing said blades in said slots; means arranged to direct braid to said blades, in successive positions for winding a plurality of coils thereon and to intermittently shift to the successive positions of the respective coils, including a slide bar mounted to slide in bearings on said frame parallel with said shaft; a pair of guide roller shafts fixed on said slide bar, in spaced parallel relation therewith; a pair of guide rollers mounted to turn idly on said roller shafts; collars adjustably rigidly connected with said shafts upon axially opposite sides of said braid guide rollers; friction disks interposed between said collars and said guide rollers; a tension device including a stationary guide plate carried by said slide bar and a spring pressed plate opposed to said stationary plate, arranged

105 110 115 120 125 130

to press a braid between them; the passageway between said plates being in alinement with said guide rollers; means arranged to shift said slide bar, step by step, axially with respect to said winding head, including a series of ratchet teeth on said bar, a pawl arranged to selectively engage said teeth, a pawl plunger, carrying said pawl, and mounted to reciprocate in bearings in said frame parallel with said slide bar, a spring normally tending to thrust said plunger to one extreme of its range of movement; means arranged to adjustably vary the pressure of said spring; means on said plunger arranged to limit the range of its movement by said spring; a series of detent notches in said slide bar, and a detent arranged to successively engage said detent notches; means arranged to actuate said pawl, at the completion of each coil, including a worm on said winding shaft; a worm gear engaging said worm; a cam shaft carrying said worm gear, journaled in bearings on said frame; and a pawl cam on said cam shaft, arranged to engage said pawl plunger, retract said plunger against the stress of said spring, and release said plunger to be operated by said spring, once each revolution of said cam shaft; and means arranged to vary the tension upon said braid in correspondence with the variations in extent of the successive convolutions in each of said coils of braid, including a fork having a pair of tines, in spaced relation, and engaged with the braid between said tension plate and said guide rollers; a rock shaft carrying said fork and journaled in said frame parallel with said winding shaft; a crank on said fork shaft; a fork actuating lever fulcrumed on said frame and having its free end pivotally connected with said link, and a spring tending to shift said lever and fork to one extreme of their range of movement; a cam on said cam shaft, arranged to cooperate with said fork lever to gradually shift the latter and turn said fork from one extreme to the other during each revolution of said cam shaft; said slide bar carrying said guide rollers and tension device being so constructed and arranged as to be normally detained in stationary position by said detent, but being intermittently shifted to the extent of one of said ratchet teeth, at each revolution of said cam shaft, which corresponds with the completion of winding a single coil in said hank.

8. In a braid hank winding mechanism, the combination with a frame; of a winding shaft mounted to rotate in said frame; means on said shaft whereby it may be rotated; a winding head on said shaft; blades carried on said head; spools on said head; means arranged to direct hank binder string from said spools through the respective blades; means arranged to direct braid to said blades, in successive positions for wind-

ing a plurality of coils thereon and to automatically shift to the successive positions of the respective coils.

9. In a braid hank winding mechanism, the combination with a frame; of a winding shaft mounted to rotate in said frame; means on said shaft whereby it may be rotated; a winding head detachably secured on said shaft, at one end thereof, including a bar extending in diametrical relation with said shaft and having slots extending in its ends in planes parallel with the axis of said shaft; blades respectively carried in said slots, each including a screw threaded shank fitted to extend through one of said slots and provided with a nut; each of said blades having a braid abutment flange fixed thereon adjacent to its screw threaded end; means whereby said blades may be relatively shifted to release a hank, including a carriage for one of said blades, fitted to reciprocate in said bar, local to one of the slots in the latter; means arranged to vary the radial position of said carriage and its blade in said bar, including a crank carried by a shaft extending transversely in said bar, and a link pivotally connected at one end to said carriage and at the other end to said crank, and an operating handle on said crank shaft; whereby said crank and link are operable as a toggle connection between said carriage and bar; means arranged to direct braid to said blades, in successive positions for winding a plurality of coils thereon and to automatically shift to the successive positions of the respective coils, including a slide bar mounted to slide in bearings on said frame parallel with said shaft; a pair of guide roller shafts fixed on said slide bar, in spaced parallel relation therewith; a pair of flanged guide rollers mounted to turn idly on said roller shafts; collars adjustably rigidly connected with said shafts adjacent to said braid guide rollers; friction disks interposed between said collars and said guide rollers; a tension device including a stationary guide plate carried by said slide bar and a spring pressed plate opposed to said stationary plate, arranged to press a braid between them; the passageway between said plates being in alinement with said guide rollers; means arranged to shift said slide bar, step by step, axially with respect to said winding head, including a series of ratchet teeth on the under side of said bar, a spring pawl arranged to selectively engage said teeth, a pawl plunger, carrying said pawl, and mounted to reciprocate in bearings in said frame parallel with said slide bar, and a spring normally tending to thrust said plunger to one extreme of its range of movement; a series of detent rack notches in said slide bar, and a spring pressed detent plunger arranged to successively engage said detent notches; means arranged to actuate said

pawl, including a worm on said winding shaft; a worm gear engaging said worm; a cam shaft carrying said worm gear, journaled in bearings in said frame; and a pawl 5 cam on said cam shaft, arranged to engage said pawl plunger, retract said plunger against the stress of said spring, and release said plunger to be operated by said spring, one each revolution of said cam shaft; 10 whereby said slide bar carrying said guide rollers and tension device is normally detained in stationary position by said detent, but is intermittently shifted to the extent of one of said ratchet teeth, at each revolution 15 of said cam shaft, which corresponds with the completion of winding a single coil in said hank.

10. In a braid hank winding mechanism, the combination with a frame; of a winding 20 shaft mounted to rotate in said frame; means arranged to prevent axial movement of said shaft; a winding head on said shaft, including means arranged to temporarily support a coil of braid; means arranged to 25 guide a braid to said winding head; and means constructed and arranged to be automatically operated by rotation of said shaft to shift the braid guide axially with respect to said shaft, intermittently, and upon the 30 completion of a predetermined number of revolutions of said shaft, while maintaining said braid in a single piece continuous from coil to coil; whereby said braid may be automatically directed and wound upon said 35 head in a predetermined number of parallel and continuously connected convolutions.

11. In a braid hank winding mechanism, the combination with a frame; of a winding 40 shaft mounted to rotate in said frame; means arranged to prevent axial movement of said shaft; a winding head on said shaft, including means arranged to temporarily support a plurality of coils of braid in par-

allel relation; means constructed and arranged to be automatically operated by rotation of said shaft to guide a braid to said winding head; means arranged to hold the braid guide stationary during the winding 45 of a series of convolutions of braid on said head, to form a coil; and means arranged to shift the braid guide axially with respect to said shaft, upon the completion of the winding of a coil of braid on said head, while maintaining said braid in a single 50 piece continuous from coil to coil; whereby 55 said braid may be automatically directed and wound upon said head in a single piece but in a plurality of parallel coils, each including a predetermined number of convolutions. 60

12. In a braid hank winding mechanism the combination with a frame; of a winding shaft mounted to rotate in said frame; means arranged to prevent axial movement of said shaft; a winding head on said shaft, 65 including means arranged to temporarily support a plurality of coils of braid in parallel relation; means constructed and arranged to be automatically operated by rotation of said shaft to guide a braid to said 70 winding head; means arranged to hold the braid guide stationary during the winding of a series of convolutions of braid on said head, to form a coil; and means arranged to shift the braid guide at predetermined 75 intervals in the rotation of said shaft; whereby said braid may be automatically directed and wound upon said head in a single piece but in a plurality of coils each including a predetermined number of parallel 80 convolutions.

In testimony whereof, I have hereunto signed my name at Burlington, New Jersey, this 23rd day of March, 1926.

SAMUEL A. NEIDICH.
